(57) **CLAIM**

The ornamental design for a jewelry maker, as shown and described.

DESCRIPTION

FIG. 1 is a perspective view of a jewelry maker showing my new design;

FIG. 2 is a top plan thereof;

FIG. 3 is a side view thereof;

FIG. 4 is an exploded perspective view of the jewelry maker showing individual components;

FIG. 5 is a top plan view of a top cover of the jewelry maker;

FIG. 6 is a top plan view of a first component of the jewelry maker;

FIG. 7 is a top plan view of a second component of the jewelry maker;

FIG. 8 is a top plan view of a center compartment of the jewelry maker;

FIG. 9 is a top plan view of an internal compartment of the jewelry maker; and,

FIG. 10 is a top plan view of a bottom compartment of the jewelry maker.

The broken lines shown in the drawing disclosure are for illustrative purposes only and form no part of the claimed design.
